WINDOW GRATING

Bernard A. McGuinness, Belmont, Mass.

Application August 27, 1934, Serial No. 741,598

5 Claims. (Cl. 20—71)

This invention relates to window gratings for use in preventing would-be intruders from entering through windows or other openings, and pertains more particularly to improvements in the 5 type of window grating disclosed in my Patent No. 1,966,636 granted July 17, 1934.

It frequently happens that persons occupying a home or other building may wish to leave the windows open but hesitate to do so for fear that 10 an intruder will enter through the open window. To prevent such unauthorized entry either when a window is left open or is forced open by the would-be intruder, the grating of the above mentioned patent is provided with sliding bars that 15 may be readily locked in the window barring position when their protection is desired and moved to an inactive or stored position at the sides of the window when their protection is not desired.

The present invention relates to window gratings in which the bars may be readily moved to and from the window barring position as in said 20 patent, but contemplates as one feature of the invention an improved arrangement whereby the means for slidably supporting the lower ends 25 of the window bars and for locking these bars in the window barring position may be mounted below the sill board of the window sill where they are out of the way and partly concealed.

Another feature of the invention resides in the 30 means for slidably supporting the window bars and for locking them in the window barring position.

A further feature resides in a guard construction whereby a person within a room may operate the bar locking means but a person outside the window is prevented by the guard from reaching in between the bars and up under the 35 guard far enough to operate the bar releasing means.

Other features of the invention and novel combination of parts in addition to the above will be hereinafter described in connection with the accompanying drawings which illustrate good practical forms of the invention.

45 In the drawings:

Fig. 1 is a front elevation of a window provided with the grating of the present invention and shows the bars positioned in the window barring position.

50 Fig. 2 is a similar view showing the bars in the inactive or stored position at one side of the window.

Fig. 3 is a vertical sectional view of Fig. 1.

55 Fig. 4 is a view similar to Fig. 3 showing the window barring means on a larger scale.

Fig. 5 is a front elevation of the upper and lower guide rails.

Fig. 6 is an end view of the upper and lower guide rails of Fig. 5.

Fig. 7 is a side elevation of a grate bar.

Fig. 8 is a modification showing the lower guide rail of Fig. 5 as provided with anti-friction rollers.

Fig. 9 is a vertical section through the window sill showing a further modification.

Fig. 10 is a front view of the guard construction of Fig. 9.

Fig. 11 is a bottom view of locking means of Fig. 10.

Fig. 12 is a view similar to Fig. 1 but shows links connecting the grating bars and a housing 15 for these bars; and

Fig. 13 is a sectional view taken on the line 13—13 of Fig. 12.

The window grating of the present invention may be used in connection with windows of the 20 ordinary home or other building or in connection with other opening, and may be readily installed upon windows of various shapes and sizes. The window frame shown, which may be of the usual construction, has the sides 10, top portion 11, 25 and sill or bottom portion 12 and the sill is provided with the usual sill board 13 that projects into the room slightly beyond the portion 14 of the window. In the window frame are slidably mounted the upper sash 15 and lower sash 16. 30

The window grating of the present invention is formed of the grating bars 17 that are supported for sliding movement from the window barring position of Fig. 1 to their inactive or stored position of Fig. 2. These bars in the construction 35 shown have laterally bent portions adjacent their ends to which the heads 18 and 19 are secured, and each bar 17 is provided near its lower end with a bowed or approximately U-shaped portion 20 formed to clear and project inwardly under 40 the sill board 13.

The upper ends of the bars 17 are slidably supported, in the construction shown, by the channel guide rail 21 and the lower ends of these bars are slidably supported by the channel guide rail 45 22 and each of these rails is provided with a laterally facing slot 23 adapted to slidably receive the laterally extending end portion of a bar 17.

These channel rails are constructed to 50 brace and slidably receive the bar heads, and the upper guide rail 21 in the construction shown is secured to the top portion of the window frame by screws 24 while the lower guide rail is similarly secured to the lower portion of the window be- 55

neath the sill board 13 where it is out of the way and partially concealed.

It is important that means be provided for fastening the bars in spaced relation to each other along the rails in the window barring position and this is accomplished in the construction shown by forming the bar receiving notches 25 in the lower edge of the slotted portion 23 of each guide rail 21 and 22. The arrangement is such that the bars 17 may be slid along the rails 21 and 22 until they drop in the proper notches 25. The bars are locked in these notches in the construction shown by providing the lower guide rail 22 with the locking strip 26 slidably mounted in the channeled portion of the rail above the slot 23.

This strip 26 is adapted to be moved to and from a position in which it rests upon the heads 19 to hold the bars in the notches 25, and to this end the strip 26 is provided with the inclined slots 27 adapted to receive the fixed pins 28 that extend across the hollow channel rail, so that as the strip 26 is moved to the right, viewing Fig. 5, it will be elevated to release the heads 19, and when moved to the left it will move downwardly to hold the heads down as shown in Fig. 5. The strip 26 may be locked in this last mentioned position by providing within the channel rail 22 near one end thereof the key controlled lock 29 having the latch 30 adapted to engage the cooperating shouldered portion 31 formed at an end of the strip 26. The arrangement is such that as the strip is moved to the position of Fig. 5 the latch 30 will snap into engagement with the portion 31 to lock the strip in this position. Movement of the strip 26 may be effected by a pin 32 projecting from the strip 26 through an inclined slot 33 in the front face of the rail 22.

It will be apparent from the foregoing that when the protection of the bars 17 is desired they are moved along the strips 21 and 22 to the window barring position as shown in Fig. 1 and are locked in this position by the strip 26 to thereby retain each bar 17 seated in an upper and lower notch 25. When the protection of the bars is no longer desired the strip 26 is unlocked and raised whereupon the bars 17 may be lifted out of the notches 25 and slid along the guide rails to an inactive position at a side of the window as shown in Fig. 2, and since the lower bar supporting rail 22 is beneath the sill board 13 it is out of the way and does not interfere with the usual use of the window sill.

In the modified construction of Fig. 8 the lower channel guide rail 22 is provided with the anti-friction rollers 34 secured in the lower portion of the channel rail by the pins 35 so that the bar heads 19 will ride upon these rollers in moving from one notch 25 to the other and travel more easily along the rail.

In some cases it may be desirable to provide means other than the key controlled lock of Fig. 5 to secure the grating bars in place, and Figs. 9, 10 and 11 show a modified construction in which the means for shifting the locking strip 26 and holding it in the locked position is accessible to a person in a room but can not be reached by a person at the outside of the window and reaching in between the grating bars. In this modified construction the bar 26 is operated by a pin 36 projecting downwardly through a slot 37 in the lower wall of the channel rail, and access to the pin by a person outside the window is prevented by a guard 38 which extends downwardly from the rail 22 or sill board 13 far enough to prevent a person from reaching in between the bars 17 and

up under the guard 38. The ends of this guard may be closed along its vertical edges by the inwardly turned portions 39 and the guard may be further anchored in place by the pins 40. The locking strip 26 may be further held in its bar locking position by the pivoted stop 41 pivoted to the lower wall of the rail 22 by the pin 42 and adapted to be swung to and from a position in which it blocks the sliding movement of the pin 36.

In Fig. 12 a construction is shown in which the grating bars 17 when moved to the sides of the window are concealed by the housings 43. These housings may be formed of sheet metal and secured to an outer edge of the side frames 10 to 15 extend over the bars 17 when in their stored position, and the bars may be held in this stored position by a spring clip 43' positioned near the entrance to the housing 43 as shown in Fig. 13.

Should it be desired to connect the bars 17 to 20 facilitate their movement to and from the window barring position, the bars may be provided with the connecting links 44 pivoted to each other at 45 and to the bars at 46, and these links may also serve to strengthen or brace the bars between 25 their ends.

When desired the bar supporting rails 21 and 22 may be sunk flush with the surface of the wood of the window frame. While the window grating has been herein described as secured to a window 30 frame, it may be attached to other structures or a special frame adjacent a window, door or other opening where the protection of the grating bars is desired. The channel rails 21 and 22 are preferably closed at their ends to limit the movement 35 of the bars 17 therein, and small openings may be provided in the lower portion of each guide rail through which dirt or water may escape.

I claim:

1. In combination with a window, a grating 40 therefor formed of vertical bars each having rail engaging means at its upper end and a laterally extending portion at its lower end that extends under the sill board of the window, a guide rail secured to the window at the upper ends of said 45 bars and a second guide rail secured to the lower portion of the window below said sill board so that the sill board and portion of the window thereabove are free from bar supporting structure, said rails being adapted to support the bars 50 for sliding movement to and from the window barring position, and means for locking the bars in spaced relation to each other along the rails to hold the bars in the window barring position.

2. In combination with a window, a grating 55 therefor formed of vertical bars having heads at their opposite ends and the bars being provided near their lower ends with laterally extending portions that extend under the sill board of the window, a guide rail secured to the window at 60 the upper ends of said bars to slidably support the heads at the upper ends of the bars, a guide rail secured to the lower portion of the window below said sill board so that the sill board and adjacent portion of the window thereabove are free 65 from bar supporting structure and the rail serves to slidably support the heads at the lower ends of the bars, whereby the bars are supported for sliding movement to and from the window barring position, and means for locking the bars in spaced 70 relation to each other along said rails to hold the bars in the window barring position.

3. In combination with a window, a grating therefor formed of vertical bars having heads at their opposite ends and the bars being provided 75

near their lower ends with laterally extending portions that extend under the sill board of the window, channel guide rails secured one to the upper portion of the window and the other to the lower portion of the window below said sill board and adapted to receive said heads and slidably support the bars for movement to and from the window barring position so that the sill board and portion of the window thereabove are free from bar supporting structure, and means for locking the bars in spaced relation to each other along said rails to hold the bars in the window barring position.

4. In combination with a window, a grating therefor formed of vertical bars having rail engaging means at their opposite ends, a guide rail secured to the window at the upper ends of said bars and a second guide rail secured to the lower portion of the window below the sill board and adapted to support the bars for sliding movement to and from the window barring position, manually shiftable means associated with the lower guide rail for locking the bars in the window barring position, and a guard extending downwardly below the lower guide rail and constructed and arranged to prevent a person outside of the window from reaching in between the bars and up

under the guard far enough to reach said manually shiftable means.

5. In combination with a window, a grating therefor formed of vertical bars having heads at their opposite ends and the bars being provided near their lower ends with laterally extending portions that extend under the sill board of the window, a guide rail secured to the window at the upper ends of said bars to slidably support the heads at the upper ends of the bars, and a guide rail secured to the lower portion of the window below said sill board so that the sill board and adjacent portion of the window thereabove are free from bar supporting structure and the rail serves to slidably support the heads at the lower ends of the bars, whereby the bars are supported for sliding movement to and from the window barring position, at least one of said guide rails having the form of a hollow channel adapted to embrace the bar heads and provided with a slot 20 that faces in a horizontal direction to slidably receive the laterally extending necks of the bars adjacent said heads, said hollow channeled rail having notches along said slot to receive the necks of said bars, and means for locking the necks in 25 said notches.

BERNARD A. McGUINNESS.
